UNITED STATES PATENT OFFICE.

THOMAS H. BRADY, OF NEW BRITAIN, CONNECTICUT.

ELECTRIC FUSE.

SPECIFICATION forming part of Letters Patent No. 653,841, dated July 17, 1900.

Application filed January 2, 1900. Serial No. 67. (No model.)

To all whom it may concern:

Be it known that I, THOMAS H. BRADY, a citizen of the United States of America, residing and having post-office address at New 5 Britain, in the county of Hartford and State of Connecticut, have invented a certain new and useful Improvement in Electric Fuses, of which the following is a description, reference being had to the accompanying drawings, wherein—

Figure 1 is a side view of an inclosed fuse embodying said improvement. Fig. 2 is a view of the same in longitudinal section on the plane denoted by the dotted line $\alpha\alpha$ of 15 Fig. 1 looking downward.

The object of the improvement is the production of an inclosed fuse for an electric circuit the burning out of which shall denote that fact exteriorly of the inclosing case.

20 In the accompanying drawings the letters a and b denote conductors adapted to form portions of an ordinary electric circuit. The letter c denotes cross-heads attached to these conductors.

25 The letters d and e denote fusible-metal parts adapted to melt at a predetermined degree of electric energy and disposed in the shape of rods. The rod d is fastened at each end to the cross-heads. The rod e is fastened 30 at one end to one of the cross-heads and at the other end to the spring f , passing inter-

mediately through the other cross-head, the hole through which it passes being slightly larger than the rod.

The letter g denotes a case inclosing the 35 fuse. The spring f extends exteriorly of the case and is there attached by its outer end to the case, so that when the apparatus is properly disposed for use the spring is under tension. Should the fuse be "burned out," the 40 fusible metal melts, whereby the spring is released and so changes its shape exteriorly of the case as to there denote that fact.

It is of the essence of my improvement that the spring itself should extend outside of the 45 inclosing case, so that no motion of another part is necessary in order to disclose the burning out of the fuse exteriorly of the inclosing case.

I claim as my improvement—

50 In an electric fuse, the combination of the conductors adapted to form part of an electric circuit, the fusible metal interposed between such conductors, the case inclosing the fusible metal, and the spring connected, under tension, to the fusible metal and extending exteriorly of the case, all substantially as described and for the purposes set forth.

THOMAS H. BRADY.
